SHOE ARCH APPLIANCE

Leo Schibi, St. Charles, Mo.

Application September 27, 1943, Serial No. 503,990

1 Claim. (Cl. 36—76)

This invention appertains to new and useful improvements in support for arches, the principal object being to provide a bridge member for interposition between the usual heel of a shoe and the ball portion thereof to provide a ground engaging structure for positively supporting the arch of a person's foot.

Other objects and advantages of the invention will become apparent to the reader of the following description.

In the drawing:

Figure 1 is a fragmentary bottom plan view showing the arch appliance.

Figure 2 is a fragmentary detailed sectional view showing the arch appliance.

Referring to the drawing wherein like numerals designate like parts, it can be seen that the arch appliance which is in fact a bridge for bridging the heel of a shoe with the ball portion of the foot is generally referred to by numeral 5 and consists of an upper layer 6 of leather and a lower layer 7 of leather and between these layers is a sheet of resilient material such as rubber and this is denoted by numeral 8. These three plies are secured together by suitable securing elements 9 and, of course, the forward end portions of these elements must be beveled in a suitable manner to meet the curvature of that portion of the shoe sole. The forward ends of the plies are

substantially broad as denoted by numeral 10, while the rear ends have somewhat of a flare 11, these latter ends being concaved so that there is only a two point contact of these ends with 5 the heel A of a shoe B to which the appliance is attached.

The appliance is attached to a shoe by suitable means 12 driven entirely through the appliance.

10 Obviously, the appliance is to be the same thickness as the heel A, to the end that a person's arch will be actually supported by engagement of this bridge or appliance with the ground.

While the foregoing specification sets forth the 15 invention in specific terms, it is to be understood that numerous changes in the shape, size and materials may be resorted to without departing from the spirit and scope of the invention as claimed hereinafter.

Having described the invention, what is claimed as new is:

20 In a shoe, an arch support attached to the shank portion of the sole of the shoe and extending from the heel to the ball portion of said sole, 25 said support comprising top and bottom plies of leather, and an intermediate ply of resilient material.

LEO SCHIBI.
